UNITED STATES PATENT OFFICE.

ROY Y. HUGHES, OF ABERDEEN, SOUTH DAKOTA, AND LOUIS J. HOFFMANN, OF BUFFALO, MINNESOTA.

DOOR-FASTENER.

1,074,261.

Specification of Letters Patent. Patented Sept. 30, 1913.

Application filed March 27, 1911. Serial No. 617,142.

To all whom it may concern:

Be it known that we, ROY Y. HUGHES and LOUIS J. HOFFMANN, citizens of the United States, residing, respectively, at 5 Aberdeen and Buffalo, in the counties of Brown and Wright, States of South Dakota and Minnesota, have invented a new and useful Door-Fastener, of which the following is a specification.

- 10 This invention relates to door fasteners of that type designed to be used in addition to the ordinary door locks and its object is to provide a simple and durable fastener of stamped metal that can be readily carried 15 in the pocket and which can be easily applied to a door so as to securely fasten it, said device being particularly useful for securing the doors of hotel rooms, state-rooms, and the like.
- 20 Another object is to provide a fastener which can be used in connection with doors and locks of different types.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

In producing a device of this character, it is essential to cheapness and practicability 35 that the same be made of as few parts and in as few operations as possible and therefore, the present fastener is composed two flat metal members, each of which is formed in two operations, namely, punching and 40 forming and without any machine work.

In the accompanying drawings, the preferred form of the invention has been shown.

In said drawings:—Figure 1 is a perspective view of the lock applied to a door which, when closed, lies flush with the jamb. Fig. 2 is a perspective view showing the fastener applied to a door and jamb having a rim lock attached thereto. Fig. 3 is a 50 horizontal section through a door and its jamb and showing the position of the fastener when a casing is secured to the jamb. Figs. 4 and 5 are detail views of the two parts of the fastener.

55 Referring to the figures by characters of

reference, 1 designates the keeper or one member of the fastener, the same consisting of an elongated thin flat strip of metal or the like having an angular off-set or jamb engaging portion 2 adjacent one end and from which a lip 3 projects, this lip being formed by one terminal of the strip. Longitudinally extending slots 4 are formed within the strip 1 and are arranged to lap. Any one of these slots is adapted to receive 60 the long arm 5 of the other member of the securer, there being an arm 6 extending from one end thereof and terminating in a right angled foot 7. This angular member composed of the arms 5 and 6 is made up of 65 a thin flat piece of metal or the like. The arm 5 has its inner long edge at right angles to the adjacent edge of the arm 6 and to the facial plane of the foot 7, while its opposite long edge converges from the arm 6 toward 70 the inner edge to produce the desired effect when the arm is inserted in one of the slots of the keeper 1.

In Fig. 1 a door has been shown at A and its jamb at B. In using the present improvement for the purpose of locking the door A in closed position, the door is swung open and the off-set portion 2 is inserted into the mortise b in the jamb B, said mortise being the one ordinarily provided to receive the bolt of the door lock. The keeper 1 will thus project between the door and the jamb and beyond the inner faces thereof. The arm 5 of the angular member is inserted into the slot 4 nearest the door and is wedged therein and against the door and jamb, the arm 6 being projected outwardly. The converging edge of this arm 5 will lap the door and jamb respectively and it will be obvious that the door cannot be opened unless angular member is first withdrawn from engagement with the strip 1. Where the jamb B has a casing, as indicated at B' in Fig. 3, the strip 1 is applied to the jamb in the same manner as illustrated in Fig. 1 but the fastening member is reversed so as to bring its foot 7 into contact with the door and the right angled edge of the arm 5 against the outer face of the casing B'. With the parts thus disposed, it will be seen that the door cannot be opened unless the angular member is first withdrawn from the strip 1.

In Fig. 2 the fastener has been shown applied to the rim lock of a door, the lock 110

casing being shown at C and the keeper being shown at D. Strip 1 is placed with its off-set portion 2 within the keeper and the wedge-shaped portion 5 of the fastening member is inserted within the slot 4 nearest the casing C and the keeper D. Said locking member will thus contact with both the casing and the keeper and the door will be securely held against opening.

10 It will be noted by referring to the drawings that both of the members of the fastener are provided with openings, such as indicated at 8. These openings are adapted to receive the ends of a cord, chain or the like utilized for the purpose of fastening the two parts together.

In manufacturing, the keeper member 1 is first formed by punching from sheet metal or ribbon metal, the staggered slots 4 and 20 the aperture 8 and the curved end adjacent the aperture 8 being simultaneously produced with the cutting or punching die which also simultaneously forms the outline, the angular offset portion 2 being produced in the second or forming operation.

25 The holding member 5, is punched from sheet metal, the aperture 8 being simultaneously produced. The stop ear 7 is then produced in the second or forming step, both members being produced from sheet metal, and without any machine work, thus producing a door fastener by the most inexpensive processes and a completed article at the final or forming step.

30 35 It will be seen that this fastener can be readily carried in the pocket and can be quickly applied to or taken from a door. When applied to a door it becomes abso-

lutely impossible to open the door from the outside.

40 What is claimed is:—

A door securer embodying a flat member insertible between the edge of a door and door jamb having jamb-engaging means and having substantially longitudinal slots 45 therein, and a flat angular member, the inner edges of which are substantially at right angles to each other and the outer edge of one arm converging toward the inner edge from the elbow of the angular member to 50 the extremity of the arm, and the other arm having its extremity bent at substantially right angles into a foot, so that the first mentioned arm of the angular member may be inserted through the slots of the 55 former member with its outer edge bearing against the faces of the door and door jamb when they are flush, and so that the first mentioned arm may be inserted through the slots with its inner edge bearing flatly 60 against the door jamb and with the foot bearing flatly against the door when the door and jamb are relatively off-set.

In testimony that we claim the foregoing as our own, we have hereto affixed our signatures in the presence of two witnesses.
